UNITED STATES PATENT OFFICE.

JESSE EARL NILES, OF PONTIAC, MICHIGAN.

ATTACHMENT FOR INTERNAL-COMBUSTION ENGINES.

Application filed September 22, 1922. Serial No. 589,960.

This invention relates to an attachment for an internal combustion engine the general object of the invention being to provide means for introducing exhaust gases into the intake manifold for increasing the effectiveness of the explosive charge.

Another object of the invention is to provide means for regulating the entrance of the exhaust gases from the throttle.

10 A still further object of the invention is to make the device so that it can be substituted for the gasket which is located between the manifold and the carbureter.

This invention also consists in certain 15 other features of construction and in the combination and arrangement of the several parts, to be hereinafter fully described, illustrated in the accompanying drawings and specifically pointed out in the appended 20 claim.

In describing my invention in detail, reference will be had to the accompanying drawings wherein like characters denote like or corresponding parts throughout the several views, and in which:—

Figure 1 is a side view of a motor showing my invention in use.

Figure 2 is an edge view with the manifolds in section.

30 Figures 3, 4 and 5 are detail views of the device itself.

As shown in these views I form the body 1 of the device of the general shape of the gasket which is located between the carbureter A and the inlet manifold B so that this device can be substituted for the said 35 gasket. It is formed with a large central opening 2 which registers with the passages in the manifold and carbureter and with the small holes 3 for receiving the bolts which hold the carbureter to the manifold. A partition 3' is formed in the hole 2 at the upper 40 part thereof and this partition is provided with an extension 4 which extends beyond the face of the body. The upper part of this partition and extension is of trough shape. A screw threaded hole 5 is formed in the upper part of the body, its lower end being in communication with the space or 45 chamber above the partition. This hole is adapted to receive the end of a valve 6, the other end of the valve receiving the pipe 7 which is connected with the exhaust manifold C so that when the valve is open some 50 of the hot gases from the manifold will pass into the space or chamber above the parti-

tion and will thus be mixed with the explosive charge passing into the inlet manifold. The valve is connected by the rod 8 with the throttle of the motor so that 60 the valve will be actuated simultaneously with the opening and closing of the throttle.

From the above it will be seen that exhaust gases will be mixed with the explosive charge as the same passes into the intake 65 manifold, thus giving more perfect combustion of the charge and in this way increasing the effectiveness of the motor. The exhaust gases striking the partition will 70 heat the same and this will act to heat the explosive charge. The partition also acts to prevent the gases from mixing with the explosive charge until they enter the intake manifold so that the charge is in the form of vapor before being mixed with the gases. 75 By connecting the valve with the throttle the proper amount of gases is admitted in accordance with the speed of the motor. This invention does away with the heating of the gasoline in the carbureter which I 80 find is a disadvantage. In my invention the explosive charge is in a dry state before it comes in contact with the exhaust gases.

It will of course be understood that the 85 supply of exhaust gases can be taken from any suitable source as I do not wish to be limited to the construction which taps the exhaust of the engine.

It is thought from the foregoing description 90 that the advantages and novel features of my invention will be readily apparent.

I desire it to be understood that I may make changes in the construction and in the combination and arrangement of the several parts, provided that such changes fall 95 within the scope of the appended claim.

What I claim is:—

An attachment of the character described comprising a body adapted to be substituted for the gasket usually placed between a carbureter and the intake manifold of an internal combustion engine, said body having relatively flat faces and a central passage providing spaced openings upon its opposite 100 sides for receiving the conventional form of fastening means therethrough securing and associating the carbureter with the intake manifold, a downwardly extending forwardly projecting trough-shaped partition 105 arranged in the upper portion of the central passage and having communication with an 110

inlet opening in the top of the body and extending an appropriate distance within the adjacent end of the intake manifold, valve controlled air inlet means arranged within the inlet opening in the top of the body and communicating with the partition, and means communicating an exhaust manifold with the valve controlled inlet means whereby exhaust gases may be introduced into the

intake manifold for heating the fuel mixture from the carburetor and force the same upwardly within the intake manifold whereby easier starting and less fuel will be attained. 10

In testimony whereof I affix my signature. 15

JESSE EARL NILES.
